RAILWAY SIGNALING SYSTEM

Henry S. Young, Wilkinsburg, Pa., assignor to
The Union Switch & Signal Company, Swiss-
vale, Pa., a corporation of Pennsylvania

Application July 28, 1936, Serial No. 93,030

19 Claims. (Cl. 246—46)

My invention relates to railway signaling systems of the type involving light signals which are approach lighted, and is an improvement on the system disclosed in my related copending application, Serial No. 742,095, filed August 30, 1934. Specifically, my invention relates to signaling of the type described wherein the signals involved include at least two lamps and wherein the continuity of the filaments of both lamps of a signal are checked while such lamps are extinguished.

The present application is also an improvement on the signaling system disclosed in a copending application for Letters Patent of the United States, Serial No. 84,498, filed by P. H. Crago on June 10, 1936, which latter application contains claims which cover broadly certain features of the herein-described signaling system.

I will describe several forms of railway signaling systems embodying my invention, and will then point out the novel features thereof in claims.

In the accompanying drawings, Figs. 1A and 1B are diagrammatic views which, when placed end to end in the order named, illustrate one form of apparatus embodying my invention. Figs. 2 and 3 are modifications of a portion of the apparatus shown in Fig. 1A, and each also embodying my invention.

Similar reference characters refer to similar parts in each of the several views.

Referring first to Figs. 1A and 1B, the reference characters 7 and 8 designate the rails of a stretch of railway track over which traffic normally moves in the direction indicated by the arrows. The rails 7 and 8 are divided, by insulated joints 9, into a plurality of sections W—X, X—Y, and Y—Z. Each section is further divided, as here shown, into two subsections 1T, 2T, 3T, 4T, etc. Each subsection is provided with a track battery 10 connected across the rails at one end of the subsection and with a track relay, designated by the reference character R with a prefix the same as the reference character of the associated subsection, connected across the rails at the other end of the subsection.

Located adjacent the entrance end of each track section is a signal each designated by a suitable distinguishing reference character and each including an upper indication unit U and a lower indication unit L. Each indication unit, as here shown, is of the type commonly known as a searchlight signal. Referring to signal 12, for example, the units of that signal each comprise an armature 16 mounted to rotate between an intermediate position to which it is biased,

and two extreme positions. Each armature 16 is controlled by an armature winding 17, and is polarized by the field from a permanent magnet or an electromagnet (not shown) in such manner that when the winding 17 is energized, the armature will rotate to its left-hand or right-hand extreme position according as winding 17 is then supplied with current of normal or reverse polarity, respectively. Attached to each armature 16 to rotate therewith are three colored roundels G, R, and Y, which are arranged to be disposed in the path of a beam of light projected from an associated lamp UE or LE according as the armature 16 occupies its left-hand extreme position, its intermediate position, or its right-hand extreme position, respectively. For convenience in illustration, each lamp UE and LE in the drawing is shown disposed above the associated roundels, but it will be readily understood that in actual practice each lamp will be located directly back of the associated roundels and will have associated therewith a suitable optical system, not shown, for projecting a beam of light from the lamp. Operatively connected with each armature 16 is a circuit controller comprising two movable contact fingers 18 and 19. The movable contact finger 18 cooperates with a fixed contact 20 to close a contact 18—20 when the armature 16 occupies its left-hand extreme position, and with a fixed contact 21 to close a contact 18—21 when the armature occupies its intermediate position or its right-hand extreme position; while the movable contact finger 19 cooperates with a fixed contact 22 to close a contact 19—22 when the armature occupies its right-hand extreme position, and with a fixed contact 23 to close a contact 19—23 when the armature occupies its intermediate or its left-hand extreme position. A signal of the type described is disclosed and claimed in Letters Patent of the United States No. 1,864,224, granted to Wesley B. Wells, on June 21, 1932, for Light signals.

For governing the signals, each section is provided with a neutral signal control relay and with a polarized signal control relay designated by the reference characters HR and DR, respectively, each with a prefix the same as the reference character of the associated signal.

For governing the relays HR and DR, each section is provided with two line circuits each including a pair of conductors which extend to the signal for the section next in advance of the associated section.

For governing the lamps UE and LE of the

signals, each section is provided with an approach lighting relay designated by the reference character ER with a prefix the same as the reference character of the associated signal. The lamps 5 UE and LE are controlled in such a manner as to become lighted whenever the associated relay ER is released, and the relays ER are controlled in such a manner as to become released whenever the associated section or the section 10 next in rear becomes occupied.

Each section is provided with a suitable source of direct current and with a suitable source of alternating current, the terminals of which are designated by the reference characters B and C, 15 and BX and CX, respectively.

For governing the character of the current supplied to the lamps UE and LE, each section is provided with a power-off relay designated by the reference character PO with a prefix the same 20 as the reference character of the associated signal. That is, the current for the energization of the lamps UE and LE is supplied from the associated terminals BX and CX or from the associated terminals B and C according as the associated 25 relay PO is energized or deenergized, respectively. The relays PO are governed in such a manner as to be energized only when the source of alternating current is present. The current for lighting the lamps, therefore, is normally supplied 30 from the alternating current source but is automatically switched over to the direct current source when the alternating current is absent.

For governing the polarity of the current supplied to the relay DR for the section next in rear, 35 each section is provided with a pole changing relay designated by the reference character PC with a prefix the same as the reference character of the associated signal.

For controlling the relays PC and the current 40 supplied for the control of the relay DR for the section next in rear as well as for governing the lower mechanism of the associated signal, each section is provided with an auxiliary relay designated by the reference character LOP with a 45 prefix the same as the reference character of the associated signal.

For at times controlling the relays LOP, each section is provided with a lightout relay designated by the reference character LO with a prefix 50 the same as the reference character of the associated signal. Each relay LO is connected in series with the upper lamp UE of the associated signal whenever the associated approach lighting relay ER is released. Connected across the 55 winding of each relay LO is an asymmetric unit 24 for the purpose of bypassing each half wave of alternating current. It will be apparent, therefore, that each relay LO will become energized whenever the upper lamp UE of the associated 60 signal is lighted either by alternating current or by direct current.

Each auxiliary relay LOP is provided with two 65 energizing circuits. Referring to signal 14, for example, relay 14LOP is normally energized by a circuit which passes from terminal B through front point of contact 25 of relay 14ER, filament 26 of lamp UE of signal 14, wire 27, filament 28 of lamp LE of signal 14, front point of contact 29 of relay 14ER, back point of contact 30 of relay 70 14LO, and relay 14LOP to terminal C. When relay 14LO is energized, however, relay 14LOP is provided with another energizing circuit which passes from terminal B over front point of contact 30 of relay 14LO and relay 14LOP to terminal 75 C. Relay 14LOP, therefore, is energized whenever

the associated lamps are dark provided the filaments of both such lamps are intact and also whenever the upper lamp of signal 14 is burning. It is understood, of course, that the resistance of relay 14LOP will be of such value that the current required by this relay will not be sufficient to light lamp filaments 26 and 28. 5

Each relay LOP is provided with control circuits similar to those just described for the relay 14LOP. 10

Associated with each section is an automatic train stopping device and a control relay designated by the reference characters V and VR, respectively, each with a prefix the same as the reference character of the associated signal. The 15 clearing circuits for the train stopping devices V will become closed only when the associated relay VR is energized so that its front contact 51 is closed. The relays VR will become energized only when the associated relays HR and PC are 20 energized provided the associated relay DR is energized in the normal direction. It is understood, of course, that the automatic train stopping devices V are not necessary to the operation of the system and may, therefore, be eliminated if 25

Having thus described in general the apparatus shown in Figs. 1A and 1B, I will now describe the operation of the system.

Each of the signals is controlled by the associated relays HR and DR in the following manner: When relay HR is deenergized (see signal 15), windings 17 of both the upper and lower mechanisms U and L of that signal are deenergized and relay 15ER also is deenergized so that 35 both lamps UE and LE of signal 15 are lighted to cause the signal to display a red light over a red light to indicate "stop". The circuit for lamp UE may be traced from terminal BX through front point of contact 31 of relay 15PO, relay 15LO 40 and asymmetric unit 24 in multiple, back point of contact 32 of relay 15ER, filament 26, back contact 33 of relay 15ER, and front point of contact 34 of relay 15PO to terminal CX. The circuit for lamp LE may be traced from terminal BX 45 through front point of contact 31 of relay 15PO, reactor 35, back point of contact 36 of relay 15ER, filament 28, back contact 33 of relay 15ER, and front point of contact 34 of relay 15PO to terminal CX. The reactance of reactor 35 is approximately 50 equal to the reactance of relay 15LO so that the current received by lamps UE and LE will be substantially uniform. Consequently, both lamps will display an indication of substantially the same intensity. 55

When relay HR is energized and relay DR is deenergized (see signal 14), the upper mechanism U of that signal is energized in the reverse direction and the lower mechanism L is deenergized so that, when the lamps UE and LE become 60 lighted, signal 14 will display a yellow light over a red light to indicate "approach". The circuit for mechanism U may be traced from terminal B through front contact 37 of relay 14HR, back point of contact 33 of relay 14DR, winding 17 of 65 mechanism U, back point of contact 39 of relay 14DR, and front contact 43 of relay 14HR to terminal C.

When relay HR is energized and relay DR also is energized in the reverse direction (see signal 70 13), the upper mechanism U is energized in the reverse direction and the lower mechanism L is energized in the normal direction so that, when lamps UE and LE of signal 13 become lighted, that signal will display a yellow light over a green 75

light to indicate "approach medium". The circuit for the upper mechanism U may be traced from terminal B through front contact 41 of relay 13HR, reverse polar contact 42—43 of relay 13DR, 5 front point of contact 44 of relay 13DR, winding 17 of mechanism U, front point of contact 45 of relay 13DR, reverse polar contact 46—47 of relay 13DR, and front contact 48 of relay 13HR to terminal C. The circuit for the lower mechanism L may be traced from terminal B through 10 front contact 41 of relay 13HR, front contact 49 of relay 13LOP, contacts 19—22 and 18—21 of mechanism U of signal 13, front contact 50 of relay 13DR, reverse polar contact 51—52 of relay 13DR, winding 17 of mechanism L, reverse polar contact 53—54 of relay 13DR, front contact 55 of relay 13DR, and front contact 48 of relay 13DR to terminal C. From the last mentioned circuit, it will be seen that the lower mechanism L can- 15 not be energized unless the associated auxiliary relay LOP also is energized and then only if the associated upper mechanism U is in a condition for the display of a yellow light.

When relay HR is energized and relay DR is 20 energized in the normal direction (see signal 12), the upper mechanism U is energized in the normal direction over easily traced circuits and the lower mechanism L is deenergized so that, when the lamps UE and LE of signal 12 become lighted, 25 that signal will display a green light above a red light to indicate "proceed".

As here shown, a train K occupies the section immediately to the right of location Z so that relay 15HR is deenergized to cause signal 13 to 30 display the "stop" indication and relay 14HR is energized to condition signal 14 for the display of the "approach" indication. The circuit for relay 14HR may be traced from terminal B at signal 15, through resistor 60, back point of contact 61 of relay 15HR, front contact 62 of relay GTR, front contact 63 of relay 5TR, relay 14HR, front contact 64 of relay 5TR, and front contact 65 of relay 5TR to terminal C. The resistance of resistor 60 is approximately equal to the resistance of the associated relay ER so that the energization of the relay HR for the section next in rear is maintained at a substantially uniform value regardless of whether the relay HR for the section in advance is energized or deenergized. 40 The circuit for each of the relays HR is similar to that described for the relay 15HR except that when the relay HR for the section in advance is energized the approach lighting relay ER for such advance section should be substituted for the 45 resistor 60.

Since relay 14HR is energized and relay 14DR is deenergized, so that signal 14 is in a condition to display the approach indication, relay 13DR also is energized in the reverse direction to condition signal 13 for the display of the "approach medium" indication. The circuit for relay 13DR may be traced from terminal B at signal 14, through front contact 37 of relay 14HR, front contact 66 of relay 14LOP, contacts 19—22 of upper mechanism U of signal 14, back point of contact 67 of relay 13PC, relay 13DR, front contact 68 of relay 13HR, back point of contact 69 of relay 14PC, and front contact 70 of relay 14HR to terminal C.

50 Since relay 13HR is energized and relay 13DR also is energized in the reverse direction so that signal 13 is in a condition to display the "approach medium" indication, relay 13PC is energized by a circuit which passes from terminal B 55 through front contact 41 of relay 13HR, front

contact 49 of relay 13LOP, contacts 22—19 and 18—21 of upper mechanism U of signal 13, front contact 50 of relay 13DR, reverse polar contact 51—52 of relay 13DR, contact 20—18 of lower mechanism L of signal 13, relay 13PC, and front contact 48 of relay 13HR to terminal C.

In view of the fact that signal 13 is in condition to display the "approach medium" indication, that both relays 13HR and 13PC are energized, and that relay 13DR is energized in the reverse direction, relay 12DR is energized in the normal direction over a circuit which passes from terminal B at signal 13 through front contact 41 of relay 13HR, front contact 49 of relay 13LOP, contact 22—19 of upper mechanism U of signal 13, front contact 71 of relay 13PC, front contact 72 of relay 12HR, relay 12DR, front point of contact 73 of relay 13PC, and front contact 74 of relay 13HR to terminal C.

Since relay 12HR is energized and relay 12DR is energized in the normal direction so that signal 12 is in a condition to display the "proceed" indication, relay 12PC is energized by a circuit which passes from terminal B through front contact 75 of relay 12HR, front contact 76 of relay 12LOP, contacts 29—18 and 19—23 of upper mechanism U of signal 12, contacts 23—19 and 21—18 of lower mechanism L of signal 12, relay 12PC, and front contact 77 of relay 12HR.

Since signal 12 and associated apparatus is in its normal condition, the line circuit for the control of the relay DR (not shown) for the section next in the rear is supplied with current in the normal direction over a circuit which includes front contact 75 of relay 12HR, front contact 76 of relay 12LOP, contact 20—18 of upper mechanism U of signal 12, and front points of contacts 78 and 79 of relay 12PC. The signal (not shown) for such section next in rear, therefore, will be in a condition to display the normal proceed indication.

The relays PC are provided with a slow release characteristic so that tumble-down of the signal circuits to the rear will be avoided when the mechanisms of the associated signal are caused to change from one condition to another condition. For example, when the train K departs from the section immediately to the right of signal 15 so that signal 13 will be caused to assume a condition for the display of the normal proceed indication, the circuit for relay 13PC will be momentarily opened while contacts 18 and 19 of signal 13 are changing their positions. Due to the slow releasing characteristic of relay 13PC, however, front points of contacts 71 and 73 of relay 13PC will not become opened to disturb the energization of the line circuit to the rear.

The relays DR are preferably provided with a retained neutral characteristic to avoid a momentary display of the yellow over red indication when the associated signal is changing from the yellow over green indication to the green over red indication. For example, if the relays DR are provided with a retained neutral feature then, 60 when the direction of energization of relay 13DR is changed from reverse to normal to cause signal 13 to assume the condition for the display of a green light over a red light, the front points 44, 45, 50 and 55 of relay 13DR will not become 65 opened. No change in the condition of signal mechanism U or L, therefore, takes place until polar contacts 43, 46, 51 and 54 of relay 13DR actually move. Since these contacts move simultaneously, the upper and lower mechanisms 70 75

of signal 13 are caused to change their conditions at substantially the same instant and a momentary condition for the display of a false indication is avoided.

5 The relays HR are provided with a slow pickup characteristic to avoid the possibility of the associated signal momentarily assuming a condition for the display of a false proceed indication when a short car or train moves at high speed from 10 one section into another in advance of the signal. For example, if a light engine should vacate subsection 1T and enter subsection 2T at such speed as to cause relay 1TR to become energized before relay 2TR becomes released, then the circuit for 15 the energization of relay 12HR would be momentarily closed until such time as relay 2TR becomes released. Since the slow pickup characteristic of relay 12HR, however, prevents the closing of the front contacts of this relay during such 20 periods, signal 12 would be prevented from assuming a false, less restrictive condition.

When a signal and associated apparatus occupies its normal condition as shown at signal 12, then the associated relay VR becomes energized 25 to close the clearing circuit for the automatic train stopping device associated therewith. For example, the circuit for relay 12VR passes from terminal B through front contact 80 of relay 12PC, relay 12VR, normal polar contact 81-54 30 of relay 12DR, front contact 82 of relay 12DR, and front contact 71 of relay 12HR to terminal C. Relay 12VR, therefore, can be energized only if the sections W-X, X-Y, and Y-Z are unoccupied 35 and then only if the filaments of the lamps for the signals associated with such sections are intact. Each of the relays VR is controlled in a manner similar to that described for the relay 12VR.

Having thus described the operation of the 40 signaling system, I will now describe the lightout protection afforded by the apparatus embodying my invention.

For example, I shall assume that with all 45 apparatus in the condition shown in the drawings, that either filament 26 or filament 28 of the lamp UE or lamp LE, respectively, of signal 14 becomes broken so that relay 14LOP becomes released. When relay 14LOP is released, the opening of its 50 front contact 66 will disconnect energy from relay 13DR so that signal 13 will be caused to assume a condition for the display of the "approach" indication. When signal 13 assumes this condition, signal 12 will be caused to assume the condition 55 for the display of the "approach medium" indication. Consequently, the open filament of either lamp UE or lamp LE, when such filaments are dark, will cause the next two successive signals in the rear to display more restrictive indications than they would ordinarily display. An engineer 60 man approaching signal 14, therefore, would receive two restrictive indications before reaching signal 14 so that he would have ample time to prepare to stop at the signal having the defective lamp.

65 If, for example, filament 26 of lamp UE at signal 13 should become burned out so that relay 13LOP becomes deenergized, then energy would be disconnected from the lower mechanism L of that signal to cause such mechanism to assume 70 a condition for the display of a red light. An approaching train, therefore, occupying section W-X would find signal 13 displaying a single red light instead of a single green light. In other words, the relay LOP provides not only for the 75 display of distinctive indications at signals in

the rear of a signal at which a lamp is burned out but also prevents, when the upper lamp of such signal is burned out, the display of the lower green light which might be mistaken for the upper green light.

5 Referring next to Fig. 2, I have illustrated herein a single signal and associated apparatus, a plurality of which when connected in a signaling system, will provide three-block, four-indication, signaling similar to that just described 10 for the apparatus shown in Figs. 1A and 1B. That is, if a plurality of signals and associated apparatus similar to that shown in Fig. 2 are embodied in a system with wires 84, 86, and 88 at 15 the right of Fig. 2 connected to wires 85, 87, and 89 at the left of Fig. 2, the system formed thereby will provide three-block, four-indication, 20 signaling. The principal difference between the arrangement shown in Fig. 2 and that shown in Figs. 1A and 1B is that the upper and lower 25 mechanisms of the signal are controlled directly over the line circuits without the use of the relays HR and DR. As will be explained more in detail hereinafter, there is also some modification in the control of the signal for the section next in rear 30 and in the control of the relays PC, VR, and ER, as well as in the control for the lower mechanism L. The control of the relays PO, LO, and LOP is identical to that described for the apparatus shown in Figs. 1A and 1B.

35 The reference characters HP and DP designate repeating relays which become energized only when the upper mechanism U of the signal is in condition to display a yellow light and a green light, respectively. The easily traced circuit for relay HP includes contacts 18-21 and 19-22 of upper mechanism U, and the easily traced circuit for relay DP includes contact 18-20 of upper mechanism U.

40 When the upper mechanism U is energized in the reverse direction, the relay HP becomes picked up and the relay DP becomes released, so that a path is completed for connecting lower mechanism L to wires 84 and 88. This path includes back contact 97 of relay DP, front contact 98 of relay HP, and front contact 99 of relay LOP.

45 When the signal is in condition to display the "stop" indication, relays PC, HP, and DP will all become deenergized and current will be supplied in the reverse direction over a path which includes wires 85 and 87 to cause the signal (not shown) next in rear to assume the condition for the display of the "approach" indication. This path also includes resistor 60, back point of contact 99 of relay DP, back point of contact 91 of relay HP, and back points of contacts 92 and 93 of relay PC.

50 When the signal is in condition to display the "approach" indication, relay HP will become energized and current will be supplied in reverse direction over a path which includes wires 85 and 87 as well as in the normal direction over a path which includes wires 85 and 89, so that the signal (not shown) next in rear will assume the condition for the display of the "approach medium" 55 indication. The first mentioned path includes relay ER, front point of contact 91 of relay HP, and back points of contacts 92 and 93 of relay PC. The second mentioned path includes front contact 94 of relay LOP, front contact 95 of relay HP, and back contacts 96 and 93 of relay PC.

60 When the signal is in condition to display the "approach medium" indication, relay PC becomes energized and current is supplied in the normal direction over a path which includes wires 85 75

of contacts 111 and 112 of relay PC. The second mentioned path includes front contact 118 of relay HP and back contacts 111 and 120 of relay PC.

- 5 When relay HD is energized in the reverse direction, when wires 104 and 108 (which correspond to wires 105 and 109) are energized in the normal direction and when relay HP is energized, the upper mechanism U remains energized in the 10 reverse direction and the lower mechanism L becomes energized in the normal direction to cause the signal to display the "approach medium" indication. The circuit for the lower mechanism L includes in addition to wires 104 and 108, front 15 contact 121 of relay HD, reverse polar contact 122-123 of relay HD, and front contact 124 of relay HP.

When the signal is in condition to display the "approach medium" indication, relay PC becomes energized so that current is supplied in the 20 normal direction over wires 105 and 107 to the relay HD (not shown) for the section next in rear. The circuit for relay PC may be traced from terminal B through front contact 125 of 25 relay HP, contacts 20-18 and 23-19 of lower mechanism L, front contact 126 of relay HD, and relay PC to terminal C.

When the relay HD is energized in the normal direction, as shown in the drawings, the upper 30 mechanism U becomes energized in the normal direction so that the signal will assume the condition for the display of the normal proceed indication. The circuit for mechanism U may be traced from terminal B through normal polar 35 contact 127-117 of relay HD, front contact 116 of relay HD, winding 17, front contact 115 of relay HD, and normal polar contact 114-128 of relay HD to terminal C.

When the signal is in condition to display the 40 normal "proceed" indication, as shown in the drawings, relay PC becomes energized by another circuit to supply current in the normal direction to wires 105 and 107 so that the signal (not shown) for the section next in rear will also be in condition to display the normal "proceed" 45 indication. This circuit for relay PC may be traced from terminal B through front point of contact 25 of relay ER, filament 26 of lamp UE, wire 27, filament 28 of lamp LE, front point of contact 29 of relay ER, back point of contact 30 50 of relay LO, contact 18-20 of upper mechanism U, contacts 21-18 and 23-19 of lower mechanism L, front contact 126 of relay HD, and relay PC to terminal C.

If either lamp filament 26 or 28 becomes 55 burned out, when the signal and associated apparatus is in the normal condition, then relay PC will become deenergized to supply current to wires 105 and 107 in the reverse direction. If either lamp becomes burned out, when the signal 60 is in condition to display the "approach medium" indication, that is, when relays HP and PC are both energized, relay HP will become deenergized so that the lower mechanism L will assume the condition for the display of the red light and 65 so that relay PC will become deenergized to supply current to wires 105 and 107 in the reverse direction. If either lamp filament 26 or 28 becomes burned out when the signal and associated apparatus is in condition to display the "approach" 70 indication, that is, when relay PC is deenergized and relay HP is energized, relay HP will become deenergized to disconnect energy from wire 109. It will be seen, therefore, that if either filament becomes burned out when the 75

signal is in condition to display one of its three proceed indications, the circuits for the control of the signal (not shown) for the section next in rear will be in condition for the display of the "approach" indication.

5

If the upper filament 26 becomes burned out when the signal is in condition to display the yellow over green or "approach medium" indication and when a train is approaching the signal, the relay HP will become released by the opening of front point of contact 30 of relay LO to cause the lower mechanism L to display a red light.

10

The relay PC is provided with a slow release characteristic to avoid tumble-down of the signal 15 circuits to the rear during periods while the control of relay PC is being transferred from one circuit to another circuit. For example, when relay PC is being transferred from control by front contact 125 of relay HP to control by the 20 lamp filaments 26 and 28, the front contacts 111 and 112 of relay PC do not become opened so that the energization of the line circuit to the rear is not disturbed.

15

The relay HP also is provided with a slow release characteristic so that the circuits controlled by this relay will not become opened during the time relay HP is being transferred from control by contacts 19-22 and 18-21 of upper mechanism U to control by contacts 18-20 30 of upper mechanism U.

25

Relay HD is preferably provided with a retained neutral characteristic so that the circuits for the control of mechanism U are not held open any longer than necessary during pole changing 35 periods. For example, if relay HD is provided with this feature then, when the energization of relay HD is changed from the reverse direction to the normal direction, front contacts 115 and 116 of relay HD do not become opened, consequently, the winding 17 of mechanism U is without energy only during the time polar contacts 114 and 117 move from their reverse position to their normal position.

40

Relay HD is provided with a slow pickup characteristic for the same reason relay HR shown in 45 Figs. 1A and 1B is provided with such feature, that is, to prevent the momentary display of a less restrictive indication while a high speed light engine is moving from one track circuit into another track circuit in advance.

50

Relay VR is energized only when the relay HD is energized in the normal direction and then only if the relay PC also is energized. That is, the clearing circuit for stop V is closed only if the 55 relays HD and PC are in condition for the normal proceed indication. The circuit for relay VR may be traced over front contact 130 of relay HD, normal polar contact 131-132 of relay HD, front contact 133 of relay PC and relay VR to terminal C.

60

From the foregoing description of each of the forms of apparatus embodying my invention, it will be seen that I have shown and described herein, lightout protection schemes as applied to 65 three-block, four-indication, signaling systems wherein if a lamp filament becomes burned out while the signal is dark, the next two signals in the rear will be caused to assume a condition for the display of a restrictive indication and where- 70 in if the lamp of the upper unit of a signal becomes burned out, the lower unit of that signal will be caused to assume a condition for the display of a red light.

Although I have herein shown and described 75

and 87 so that the signal (not shown) next in rear will assume the condition for the display of the normal "proceed" indication. The circuit for relay PC may be traced from terminal B through 5 contacts 20-18 and 19-23 of lower mechanism L, front contact 100 of relay LOP, and relay PC to terminal C. The path including wires 85 and 87 also includes relay ER, and front points of contacts 93 and 92 of relay PC.

- 10 When the signal is in condition to display the normal "proceed" indication, relay DP becomes energized over its previously mentioned circuit and the relay PC remains in its energized condition to supply current in the normal direction to 15 wires 85 and 87. This circuit for relay PC may be traced from terminal B through front contact 101 of relay DP, contacts 18-21 and 19-23 of lower mechanism L, front contact 100 of relay LOP, and relay PC to terminal C.
- 20 When the signal and associated apparatus are in condition for the display of the normal "proceed" indication, relay VR will become energized over a circuit which passes from terminal B through front contact 102 of relay LOP, front 25 contact 103 of relay DP, and relay VR to terminal C.

If either filament 26 or 28 of lamps UE and LE, respectively, becomes opened, relay LOP, of course, will be released. The opening of front 30 contact 100 of relay LOP will release relay PC so that current will be supplied in the reverse direction to wires 85 and 87, the opening of front contact 94 will prevent the energization of wire 89, the opening of front contact 99 of relay LOP 35 will prevent the energization of lower mechanism L, and the opening of front contact 102 of relay LOP will release relay VR. Therefore, if either filament becomes opened while extinguished, the signal (not shown) for the section next in rear 40 will be caused to assume the condition for the display of a yellow over a red light, the lower mechanism of the signal with which such lamps are associated will be caused, if not already in such condition, to assume a condition for the display of a red light, and the clearing circuit for 45 the automatic train stopping device associated with such signal, if not already opened, will become opened.

If the relay LOP becomes released while the 50 signal is in condition to display the normal "proceed" indication so that relay PC becomes released while relay DP remains energized, then the circuit for the control of the upper mechanism of the signal (not shown) for the section next in rear will include relay ER, front point of contact 98 of relay DP, back point of contact 91 of relay HP, back points of contacts 92 and 93 of relay PC, and wires 85 and 87.

If filament 26 of upper lamp UE is burned out, 60 then when a train is approaching the signal, relay LOP will remain deenergized so that lower mechanism L will be certain to be in condition to display a red light. If, on the other hand, filament 28 of the lower lamp LE is burned out, 65 then when an approaching train releases relay ER, the upper lamp UE will display its usual indication in accordance with traffic conditions in advance.

The relays HP and DP are each provided with 70 a slow release characteristic so that, when the upper mechanism U is changing from the condition to display a yellow light to the condition to display a green light, or vice versa, while the relay PC is deenergized, a momentary release of 75 the relay ER to cause a flash of the signal lamps

will be avoided. For example, if relay PC should become released due to the releasing of relay LOP, then energy would be supplied to back point of contact 92 of relay PC over front point of contact 90 of relay DP and back point of contact 91 of relay HP. If, under this condition, the upper mechanism U should now become energized in the reverse direction, relay DP would become deenergized and relay HP would become energized. Due to the slow releasing characteristic of relay DP, however, front point of contact 90 of relay DP would remain closed at least until front point of contact 91 of relay HP becomes closed. Relay ER, therefore, would not become released to cause a momentary flash of 15 the signal lamps.

Referring now to Fig. 3, I have shown herein one signal and associated apparatus, a plurality of which when embodied in a system with wires 104, 106, and 108 at the right of Fig. 3 connected 20 to wires 105, 107, and 109, respectively, at the left of Fig. 3, will function to provide three-block, four-indication, signaling similar to that described for the apparatus shown in Figs. 1A and 1B.

The apparatus illustrated in Fig. 3 differs from that shown in Figs. 1A and 1B principally in that, in Fig. 3, the number of line control wires is reduced and, in Fig. 3, the relay designated by the reference character HD replaces the relays 30 HR and DR shown in Figs. 1A and 1B. As will be explained more in detail hereinafter, the relay LOP is eliminated and its functions performed by the relays HP and PC. The control for the relays ER and VR is similar to that 35 shown in Figs. 1A and 1B and the control for the relays PO and LO is identical to that shown in Figs. 1A and 1B.

When relay HD becomes deenergized so that 40 the signal will display the "stop" indication, relay PC becomes deenergized so that the relay HD (not shown) for the section next in rear becomes energized in the reverse direction over a path which includes resistor 60, back point of contact 110 of relay HD, back points of contacts 111 and 112 of relay PC, and wires 105 and 107.

When relay HD becomes energized in the reverse direction, the upper mechanism U becomes energized in the reverse direction to cause the signal to display the "approach" indication. The 50 circuit for upper mechanism U may be traced from terminal B through reverse polar contact 113-114 of relay HD, front contact 115 of relay HD, winding 17 of mechanism U, front contact 116 of relay HD, and reverse polar contact 117-118 of relay HD to terminal C.

When the upper mechanism U is energized in the reverse direction, relay HP becomes energized. The circuit for relay HP may be traced from terminal B through front point of contact 25 of relay ER, filament 26, wire 27, filament 28, front point of contact 29 of relay ER, back point of contact 30 of relay LO, contacts 18-21 and 19-22 of upper mechanism U, and relay HP to terminal C.

When both relays HP and HD are energized and relay PC is deenergized, the relay HD (not shown) for the section next in rear is energized in the reverse direction over a path which includes wires 105 and 107 and the lower mechanism of the signal (not shown) for the section next in rear becomes energized in the normal direction over a path which includes wires 105 and 109. The first mentioned path also includes relay ER, front point of contact 110 of relay HD, and back points 75

only three forms of apparatus embodying my invention, it is understood that various changes and modifications may be made therein within the scope of the appended claims without departing from the spirit and scope of my invention.

Having thus described my invention, what I claim is:

1. In combination, a forward section and a rear section of railway track, a signal for the forward section controlled by traffic conditions in advance and including a pair of lamps, means effective when the rear section is occupied to light both said lamps to cause said signal to display an indication, a signal for the rear section, and means effective if the filament of either lamp is broken when both sections are unoccupied to cause the signal for the rear section to assume a condition for displaying a more restrictive indication than such signal would be in condition for if the filaments were intact.

2. In combination, a forward section and a rear section of railway track, a signal for the forward section controlled by traffic conditions in advance and including a pair of lamps, means effective when the rear section is occupied to light both said lamps to cause said signal to display an indication, a signal for the rear section, and means for controlling the signal for the rear section when both sections are unoccupied including a circuit which is then completed if and only if the filament of each lamp is intact.

3. In combination, a forward section and a rear section of railway track, a signal for the forward section controlled by traffic conditions in advance and including a pair of lamps, means effective when the rear section is occupied to light both said lamps to cause said signal to display an indication, a signal for the rear section, and means controlled in part by the filaments of both lamps effective when either filament is broken and both sections are unoccupied to condition the signal for the rear section for the display of a restrictive indication.

4. In combination, a forward section and a rear section of railway track, a signal for the forward section controlled by traffic conditions in advance and including a pair of lamps, means effective when the rear section is occupied to light both said lamps to cause said signal to display an indication, a signal for the rear section, and a relay for controlling the signal for the rear section when both sections are unoccupied, said relay being then connected in series with the filament of each lamp.

5. In combination, a forward section and a rear section of railway track, a signal for the forward section governed by traffic conditions in advance and including a pair of lamps, means for lighting said lamps when the rear section becomes occupied, a signal for the rear section governed by traffic conditions in advance, and means governed in part by the filaments of both lamps and effective if the filament of either lamp becomes broken while both sections are unoccupied to cause the signal for the rear section to assume the same condition that it would assume if the forward section were occupied and the rear section unoccupied.

6. In combination, a forward section and a rear section of railway track, a signal for the forward section governed by traffic conditions in advance and including a pair of lamps, means for lighting both lamps if either section becomes occupied, a signal for the rear section, and means for governing said signal for the rear section including a relay which is connected in a series cir-

cuit with the filaments of both lamps at all times except when either section is occupied, said relay having a sufficiently high resistance so that when the circuit for the relay is closed both lamps which are connected in series therewith will remain extinguished.

7. In combination, a forward section and a rear section of railway track, a signal for the forward section governed by traffic conditions in advance and including a pair of lamps, a normally energized approach lighting relay which becomes de-energized when the rear section is occupied, a circuit for each lamp each including a back contact of said approach lighting relay, a lightout relay connected in series with the filament for one of said lamps when said approach lighting relay is deenergized, an auxiliary relay, a circuit for said auxiliary relay including the filaments of both lamps in series as well as a front contact of said approach lighting relay and a back contact of said lightout relay, another circuit for said auxiliary relay including a front contact of said lightout relay, and a signal for the rear section governed by said auxiliary relay when both sections are unoccupied.

8. In combination, a forward section and a rear section of railway track, a signal for the forward section including a first indication unit and a second indication unit, each said unit including a mechanism and a lamp cooperating therewith to provide a plurality of different indications, means governing said mechanisms in accordance with traffic conditions in advance of the signal, means for supplying operating current to both lamps when the rear section is occupied, a relay, means for energizing said relay provided the filaments of both lamps are intact when operating current is disconnected therefrom, means for energizing said relay provided the filament of the lamp associated with the first unit is intact when lighted, a pole changing relay governed by said first mentioned relay, and a signal for the rear section governed by said pole changing relay.

9. In combination, a forward section and a rear section of railway track, a signal for the forward section including a first indication unit and a second indication unit, each said unit including a mechanism and a lamp cooperating therewith to provide a plurality of different indications, means governing said mechanisms in accordance with traffic conditions in advance of the signal, means for supplying operating current to both lamps when the rear section is occupied, a relay, means for energizing said relay provided the filaments of both lamps are intact when operating current is disconnected therefrom, means for energizing said relay provided the filament of the lamp associated with the first unit is intact when lighted, and a traffic governing device associated with said signal governed by said relay.

10. In combination, a forward section and a rear section of railway track, a signal for the forward section including a first indication unit and a second indication unit, each said unit including a mechanism and a lamp cooperating therewith to provide a plurality of different indications, means governing said mechanisms in accordance with traffic conditions in advance of the signal, means for supplying operating current to both lamps when the rear section is occupied, a relay, means for energizing said relay provided the filaments of both lamps are intact when operating current is disconnected therefrom, means for energizing said relay provided the filament of the lamp associated with the first unit is intact when lighted.

ed, a train stopping device for the forward section, a relay effective when energized to close a clearing circuit for said device, and a circuit for said last mentioned relay including a front contact of said first mentioned relay.

11. In combination, a forward section and a rear section of railway track, a signal for the forward section including a first indication unit and a second indication unit, each said unit including a mechanism and a lamp cooperating therewith to provide a plurality of different indications, means governing said mechanisms in accordance with traffic conditions in advance of the signal, means for supplying operating current to both lamps when the rear section is occupied, a relay, means for energizing said relay provided the filaments of both lamps are intact when operating current is disconnected therefrom, means for energizing said relay provided the filament of the lamp associated with the first unit is intact when lighted, a train stopping device for the forward section, a relay effective when energized to close a clearing circuit for said device, and means governed by traffic conditions in advance of said device for energizing said last mentioned relay provided said first mentioned relay is energized.

12. In combination, a forward section and a rear section of railway track, a signal for the forward section comprising a first mechanism and a second mechanism each including a lamp cooperating therewith to provide a plurality of indications, means for supplying operating current to both lamps of said signal when the rear section is occupied, a relay, means for energizing said relay provided the filaments of both lamps are intact when operating current is disconnected therefrom, means for energizing said relay provided the filament of the lamp associated with the first mechanism is intact when lighted, means for governing said first mechanism in accordance with traffic conditions in advance of the signal, and means including said relay for governing said second mechanism in accordance with traffic conditions in advance of the signal.

13. In combination, a forward section and a rear section of railway track, a signal for the forward section comprising a first mechanism and a second mechanism each including a lamp cooperating therewith to provide a plurality of indicators, means for supplying operating current to both lamps of said signal when the rear section is occupied, a relay, means for energizing said relay provided the filaments of both lamps are intact when operating current is disconnected therefrom, means for energizing said relay provided the filament of the lamp associated with the first mechanism is intact when lighted, means for governing said first mechanism in accordance with traffic conditions in advance of the signal, and a circuit for said second mechanism including a front contact of said relay.

14. In combination, a forward section and a rear section of railway track, a signal for the forward section including a first indication unit and a second indication unit, each said unit including a mechanism and a lamp cooperating therewith to provide a plurality of different indications, means governing said mechanisms in accordance with traffic conditions in advance of the signal, means for supplying operating current to both lamps when the rear section is occupied, a relay, means for energizing said relay provided the filaments of both lamps are intact

when operating current is disconnected therefrom, means for energizing said relay provided the filament of the lamp associated with the first unit is intact when lighted, a signal for the rear section, and a circuit for said signal including a front contact of said relay. 5

15. In combination, a forward section and a rear section of railway track, a signal for the forward section governed by traffic conditions in advance and including a first mechanism and a second mechanism each provided with a lamp capable of cooperating therewith to display a plurality of different indications, means for supplying operating current to the lamps of both mechanisms when the rear section is occupied, a relay, a circuit for said relay including the filaments of both lamps when operating current is disconnected therefrom and a contact closed only when said first mechanism is in a particular condition, another circuit for said relay including 20 said contact and closed only if the filament of the lamp associated with said first mechanism is intact when burning, a signal for the rear section, and a circuit for said signal for the rear section including a contact of said relay. 25

16. In combination, a forward section and a rear section of railway track, a signal for the forward section governed by traffic conditions in advance and including a first mechanism and a second mechanism each provided with a lamp capable of cooperating therewith to display a plurality of different indications, means for supplying operating current to the lamps of both mechanisms when the rear section is occupied, a relay, a circuit for said relay including the filaments of both lamps when operating current is disconnected therefrom as well as a contact closed only when said first mechanism is in a particular condition and another contact closed only when said second mechanism is in a particular condition and a signal for the rear section governed by said relay. 35

17. In combination, a stretch of railway track divided into sections, a signal for each section comprising a first mechanism and a second mechanism each responsive to the polarity of the current supplied thereto and each mechanism including a lamp cooperating therewith to provide a plurality of indications, means for each section for supplying operating current to both lamps of the associated signal when either the section next in rear or the section next in advance of such signal is occupied, a relay for each section which is energized when operating current is disconnected from the lamps of the associated signal provided the filaments of both lamps are then intact, said relay also being energized whenever the lamp of the first mechanism of the associated signal is burning, and means for each section controlled by the associated relay for 40 governing the signal for the section next in rear. 50

18. In combination, a stretch of railway track divided into sections, a signal for each section comprising a first mechanism and a second mechanism each responsive to the polarity of the current supplied thereto and each mechanism including a lamp cooperating therewith to provide a plurality of indications, means for each section for supplying operating current to both lamps of the associated signal when either the section next in rear or the section next in advance of such signal is occupied, a relay for each section which is energized when operating current is disconnected from the lamps of the associated signal provided the filaments of both lamps are 65 70 75 75

then intact, said relay also being energized whenever the lamp of the first mechanism of the associated signal is burning, and means for each section including the associated relay for insuring that the signal for the section next in rear will assume a condition for the display of a restrictive indication when such relay is deenergized.

19. In combination, a stretch of railway track divided into sections, a signal for each section comprising a first mechanism and a second mechanism each responsive to the polarity of the current supplied thereto and each mechanism including an electric lamp, each said signal being capable of displaying "stop" when the associated mechanisms are both deenergized, "approach" when the first mechanism is energized in the reverse direction and the second mechanism is deenergized, "approach medium" when the first mechanism is energized in the reverse direction and the second mechanism is energized in the normal direction, and "proceed" when the first

mechanism is energized in the normal direction and the second mechanism is deenergized; means for energizing the first mechanism of each signal in the normal direction provided the next three sections in advance of such signal are unoccupied and in the reverse direction provided either one or two sections next in advance of such signal are unoccupied, means for energizing the second mechanism of each signal in the normal direction provided the two sections next in advance of such signal are both unoccupied and the third section in advance of such signal is occupied, means for lighting both lamps of each signal when either the section next in rear or the section next in advance of the associated signal is occupied, means associated with each signal effective if the filament of either lamp of such signal is broken and both the sections next in rear and next in advance of the signal are unoccupied to condition the two signals next in rear of such signal for displaying more restrictive indications.

HENRY S. YOUNG.
